SERVICE FACILITATING EQUIPMENT

Darrell M. Johnson, Thomson, Ga.

Application July 5, 1950, Serial No. 172,158

4 Claims. (Cl. 283—66)

1

This invention relates to the scheduling and docketing of a series of service operations, the sum of which constitutes the fulfillment of a satisfactory service prescription indicating the requisite attention to mechanism in order to obtain maximum satisfactory operation and use of the same.

In addition to the scheduling, the invention relates to the distribution and integration of tasks to be performed in the fulfillment of the servicing schedule, the selection and assignment of trained or qualified personnel to perform such tasks or services, and the allocation and listing of materials which should be used in the service rendered.

Stated in greater detail, the invention relates to the keeping of records of the above character including the simplified handling of such records whether in the nature of sheets, tickets, or other data bearing or receiving material having to do with the scheduling and assignment of work along with the allocation and listing of appropriate materials and personnel, and the utilization of records relative thereto in order to simplify and facilitate the rendering of the prescribed service with minimum time loss and expense and a maximum efficiency, the overall result of which inures to the benefit of all parties concerned.

Numerous types of equipment have been employed, in the conduct of businesses, in which service is rendered to the public, in an effort to simplify and otherwise improve the operation of such businesses and to reduce the confusion, irritation, and inconvenience in connection with the same. Such prior equipment has failed to satisfactorily accomplish the desired results although in certain fields, as in the servicing of automobiles, some improvement has been obtained in an occasional more progressive establishment by the keeping of a closer tab on the service to be performed and the actual accomplishment of the same with some conservation of labor and materials.

Among the objects of the invention are to overcome the above indicated and other problems in the conduct of a business which consists largely in the service of the public, by the provision of work scheduling and personnel and material allocation equipment, of simple and inexpensive character and by the use of which a business enterprise as, for example, the servicing and maintenance of automobiles, may be simply, efficiently and satisfactorily conducted, and maximum durability or life of the automobile or other mechanical device obtained, to the advantage not only of the customer and the servicing agency, but also to the manufacturer of the automobile because of the favorable publicity resulting from such greater life of the mechanism.

Another object of the invention is to provide the proper service including lubrication and the like and in the case of automobiles to improve

2

the smoothness of operation and riding qualities thereof, as well as to teach or instil into the customer and the public, greater care and consequently increased respect for the automobile or other machinery having wearing parts, and by so doing increase the self-respect of the customer and the general public thereby promoting local thrift and, eventually, national and international prosperity.

Another object is to provide equipment of sufficient flexibility to enable its use in connection with nonanalogous services or courtesies without extra effort or expense.

Another object of the invention is to provide an attractive salable package, the contents of which are of simple and inexpensive character requiring no special skill or operator in the use of the same, but inspiring greater confidence in the employee as well as in the customer with consequent reduction in direct supervision by the employer as well as the elimination of waste in job transfer resulting in reduced overhead and lower operating costs.

A further object of the invention is to provide equipment which will be of material aid or advantage in the conduct of a business and which will afford a running inventory or estimate of anticipated business and the amount of contemplated income.

A further object of the invention is to provide equipment by the use of which the establishment employing the same will be more businesslike, better employer-employee relations as well as customer relations will exist, and the equipment will serve to constantly advertise the business by reminding the customer and the public of the particular establishment thus serving to promote, enlarge, and improve the general nature of the business.

Further objects and advantages of the invention will be apparent from the following specification and in conjunction with the accompanying drawings, wherein:

Fig. 1 illustrates a master work sheet or basic form of the present invention;

Fig. 2, a set of twelve service or work tickets arranged consecutively;

Fig. 12, an enlarged section on the line 12-12 of Fig. 8 illustrating the ticket receiving pockets and a central indicia-bearing strip;

Fig. 13, a front elevation similar to that of Fig. 8 of another form of ticket exhibiting rack;

Fig. 14, an enlarged section on the line 14-14 of Fig. 13 illustrating the manner of securing the strips forming the ticket receiving pockets in place as well as a portion of a channel member for removably receiving an indicia-bearing strip;

Fig. 15, an enlarged section on the line 15-15 of Fig. 13 showing the ticket receiving pockets;

Fig. 16, an enlarged section on the line 16-16 of Fig. 13 showing the channel for removably receiving an indicia-bearing strip and the strip in position therein,

Fig. 17, a further enlarged fragmentary section similar to those of Figs. 14 and 15 but with a ticket in one of the card-receiving pockets;

Fig. 18, a fragmentary front elevation of a further modified form of rack with a sign;

Fig. 19, a top plan view of the rack and sign of Fig. 18;

Fig. 20, an enlarged section on the line 20-20 of Fig. 18;

Fig. 20A, a fragmentary section similar to Fig. 20 showing a modified form of clamping means;

Fig. 21, a section on the line 21-21 of Fig. 18;

Fig. 22, a section on the line 22-22 of Fig. 18;

Fig. 23, a fragmentary perspective of a supporting upright or bracket as utilized in Fig. 20.

Fig. 24, a perspective of the letter "E" shown on sign in Fig. 18;

Fig. 25, a fragmentary perspective of a modified supporting upright similar to that shown in Fig. 23;

Fig. 26, a front elevation of a further modified form of sign;

Fig. 27, a section on the line 27-27 of Fig. 26;

Fig. 28, a section on the line 28-28 of Fig. 26;

Fig. 29, an enlarged perspective of a letter having securing means slightly different from that shown in Fig. 24;

Fig. 30, a perspective of a modified form of sign;

Fig. 31, a perspective of a further modified form;

Fig. 32, an elevational view of a device to facilitate coding of the tickets shown in Fig. 2 and the master sheet shown in Fig. 1; and

Fig. 33, a sectional view on the line 33-33 of Fig. 32.

Briefly stated, the invention comprises equipment including a master guide or work sheet for indicating or recording pertinent information about the customer as well as the customer's needs over a predetermined period of time, with a dispenser supplied for the customer's use containing service tickets bearing indicia for conveying information correlated with the work sheet the number of tickets supplied being sufficient for the same period of time as on work sheet and having the services to be rendered indicated by code on such tickets. The dispenser is constructed to permit visibility of the top ticket and a portion of the data thereon is a reminder indicating when the next trip to the service station is to be made. Removal of the top ticket

renders the next ticket visible and so on through the entire pack.

Also there is provided a follow up board or rack for holding the tickets received from the dispenser so that they may readily be observed and by means of which the proper scheduling of customer reminder service may be carried out.

The equipment also includes a work distribution and time adjustment rack for aiding in the allocation of the work to be performed and the amount of time to be spent on the work as well as the adjustment of the time schedule in accordance with any variations therein.

With continued reference to the drawings there is shown in Fig. 1 a master work sheet or chart 10 having a vertical Maintenance Guide column 11 with twenty-four horizontal spaces 12 for eighteen standardized maintenance or service items 13 and six additional spaces for the indication of a particular service or other items requested by the customer.

In addition to the Maintenance Guide column 11 there is a vertical Price column 14, a Mileage Interval column 15, a Last Mileage column 16, a Next Mileage column 17, a series of twelve numbered Basis Miles columns 18, 19, 20, 21, 22, 23, 24, 25, 26, 27, 28 and 29, respectively of one thousand mile intervals. There is also a Continued Mileage column 30 from which the figures can be transferred to a succeeding sheet or chart for continuing the operation when the sheet is exhausted.

Along the top of this master work sheet or chart are located spaces 31, 32, 33 and 34 for the Name and Address, Phone and License number, Make and Model and Motor and Serial number of the car, respectively.

When a customer comes into the service station or department thereof, from him is learned approximately how many thousand miles he drives per year, the kind of driving that he does, the nature of services desired, the frequency of service and all pertinent facts that will enable such service requirements to be met. If, for example, he brings his car in with 3019 miles showing on the speedometer and he drives twelve thousand miles a year, there should be approximately twelve mileage intervals of 1000 miles each during the year. However any number of service intervals may be scheduled should such prove desirable. It having been found that is one of the most frequent service requirements this lubrication appears as the first item in the Maintenance Guide column of services to be rendered adjacent the numeral 1. Accordingly the desired lubrication mileage interval is employed as a basis or key on which the chart is set up and the mileage intervals at which the customer is to come in for service. In view of the fact that there are twelve of these one-thousand mile intervals, the calls for service are approximately thirty days apart. In the Mileage Interval column the number 1000 will be recorded, in the last Mileage column 3019 will be recorded in the Next Mileage column the mileage 4019 will be placed, and such marking will be continued to the end of the succeeding Basis Miles columns.

In the Maintenance Guide column 11, eighteen standard services are indicated and two additional special services, 19 and 20, such as flushing the brake system and lubricating lawn mower are included.

Any operation or service not desired by the customer may be marked out as "Not wanted"

such as the flushing the motor service as indicated by the designation. Operations 17 and 18, namely, transmission and differential change, and radiator service are seasonal, *s1*, meaning one change during a year, and *s2*, meaning a change twice yearly.

While the lubrication operation is normally performed most frequently, certain other of the operations are intended to be performed less frequently. For example, item 4 in the Maintenance Guide column, namely, Repacking the Rear Springs, is to be done every three thousand miles and in the Last Mileage column the speedometer reading of 3019 is placed, and in the Next Mileage column three thousand miles is added and the speedometer reading of 6019 is inserted and checks are placed in the Basis Miles columns at the proper speedometer readings.

After the master chart is completed by filling in the desired information, such information is supplied to the customer. The twelve columns or Basis Miles form the twelve maintenance visits set up for the customer. He is supplied with a dispensing container holding tickets, one each for the twelve maintenance visits. The dispenser may be formed of plastic or other desired material. The twelve tickets contain in condensed coded form the information from the master work sheet. Of these tickets, the first ticket 18' has a space adjacent its top beneath the word "Miles" for the speedometer reading 4019 of the Basis Miles column 18 at which the next visit for service is to be made. Beneath this space there are twenty-four numerals corresponding to the twenty-four services listed in the Maintenance Guide column and by checking these numerals the service item of the master work sheet is recorded. The ticket 18' has operations 1, 2, 3, 5 and 8 checked which means that when the speedometer of the automobile registers 4019 miles, the car is to be taken in for service operations 1, 2, 3, 5 and 8 of the Maintenance Guide column, as indicated by checks in the first Basis Miles column. The ticket 18' is further provided with characters *s1* and *s2* appearing over numerals 17 and 18 on this and each of the other eleven tickets to indicate that these services, namely, Transmission and Differential, and Radiator service, are to be performed if it is the proper season. The remainder of the tickets 19' through 29' are similar, each succeeding ticket carrying a speedometer reading corresponding to the mileage shown in the Basis Miles column, and the respective operations checked thereunder being indicated on the coded tickets.

Each of the twelve tickets on its reverse side is divided into upper, intermediate, and lower sections 35, 36 and 37, respectively. In the upper section 35 is carried the number of the customer's account, in the lower section is the number of the ticket corresponding to the number of the Basis Miles column, and in the intermediate section is indicated the number of estimated days between visits to provide a follow up reminder. It will therefore be apparent that the only difference in these numbers is the bottom number indicating the number of the ticket.

The tickets 18' to 29' are supplied to the customer, and for convenience a plastic dispensing container 38 having a dispensing opening 39 is employed having a slot 40 through which the ticket can be engaged and thereby removed from the dispenser. In order that the tickets can be removed one at a time from the dispenser they are held upwardly by means of a pair of springs 75

41 in relation to the opening 39. The plastic dispenser 38 may be mounted in any desired manner as, for example, on a bracket 42 secured thereto by means of rivets or other fastening elements 43. This bracket may be attached to the instrument board 44 by means of a bolt or other fastening element 45 extending through the opening 46 in the bracket 42. The instrument board is conventional and preferably the plastic dispenser case 38 is in proximity to the speedometer 46 having a mileage indicator 47 so that when the speedometer is observed the dispenser 38 will likewise be observed and the customer reminded to take his car in for service.

15 At the bottom of the master work chart are Date In and Mileage In columns 48 and 49 at the foot of the Basis Miles columns 18 through 29, inclusive, for indicating the time and actual mileage when the customer comes in for comparison with the Basis Miles indicated at the proper period.

20 In Fig. 8 is disclosed a card or ticket exhibiting rack of a construction illustrative of the invention. This rack has a rear or foundation panel 60 which may be of plywood or the like and of any desired configuration, but which, for convenience of illustration, has been shown as substantially square.

25 The rear panel 60 may have an edge molding 61 there around to improve its appearance and protect the edges thereof and, if desired, this molding may have a protecting sheath or coating of metal, plastic, or other desired material.

30 As shown in Fig. 8, the panel 60 may be divided 35 into a plurality of vertically spaced recesses by ribs 62 nailed or otherwise secured to the front surface thereof and projecting outwardly any desired distance. Obviously, the configuration or spacing of these recesses may be changed, as 40 desired, without in any way departing from the instant invention.

35 In order to support a plurality of tickets on the front surface of the panel 60 so that they can be easily observed, strips or slats 63 are provided 45 which, as shown in Figs. 9 to 12, are of concavo-convex formation, these strips being preferably formed of resilient sheet metal similar to those employed in conventional Venetian blinds but, if desired, the strips may be constructed of certain plastics. The strips or slats 63 may be of any desired length corresponding to requirements 50 and the foundation panel or back board will be of corresponding dimensions. In this manner, the rack may be very economically constructed by forming the strips from an endless length of stock and detaching the same in desired lengths 55 for a particular size of rack.

60 As shown in Fig. 10, the strips 63 are arranged in parallel overlapping relation with their convex sides disposed rearwardly adjacent the front surface of the rear panel 60. The first or uppermost strip 63 may engage one of the ribs 62 and the second or next succeeding or lower strip overlaps the first and, due to its curvature, the upper edge thereof extends forwardly of and in spaced relation to the upper strip or slat 63, thus providing a space therebetween. On account of the curvature of the first or uppermost strip 63, the lower edge of the latter contacts the rear surface of the second or next succeeding or lower strip 63 along substantially the longitudinal center line thereof to provide a substantially closed pocket 64 capable of receiving a relatively thin object such as a ticket and this structure is repeated throughout the surface of the

panel 60. It will thus be seen that a plurality of horizontally disposed vertically spaced ticket receiving pockets 64 are thus formed by the strips or slats 63 disposed in the proper position just described.

The strips or slats 63 may be conveniently secured to the foundation or base panel 60 in any desired manner and may have vertically disposed horizontally spaced pressure ribs 65 firmly secured in contact with the outer surface of the strips or slats 63 by screws or other fastening means 66 anchored in the panel 60. The ribs 65 press tightly against the strips 63 and at the point of engagement therewith flatten these strips against the panel 60 to firmly secure the same thereto, however, immediately adjacent the ribs 65 the resiliency of the strips 63 is sufficient to restore the curvature thereof thereby providing sufficient space for the insertion of tickets to be engaged and held on display.

As will be seen from an inspection of Fig. 8, the ticket exhibiting rack is divided into an upper section 67 and a lower section 68, these sections in turn being divided into a plurality of horizontally spaced sections 69 by vertically disposed lines 70 applied to the surface of the strips or slats 63 in any desired manner, such as by paint of a contrasting color.

For convenience in locating the desired ticket or pocket 64 in which a ticket is to be inserted, there may be provided in the upper recess 71 an indicia-bearing strip 72 having numbers or other indicia relating to the horizontally spaced pockets and conveniently the strip 72 may comprise one of the strips 63 preferably with the convex face thereof outermost, as shown in Figs. 9 and 10. The strip 72 may be secured in position by screws 73 or other desired fastening means.

A second indicia-bearing strip 74 having numbers or other indicia relating to the horizontally spaced pockets 64 in the lower section 68 may be disposed substantially midway of the height of the rack, as shown in Figs. 11 and 12. This strip 74 may be secured in position by the same ribs 65 which secure the strips 63 to the panel 60 and preferably with the convex face of the strip thereof outermost.

The uppermost recess 75 of the vertically spaced recesses may receive a strip 76 of the same material as the strips or slats 63 and preferably as shown in Fig. 9, the convex surface thereof is outermost. The strip 76 may carry on its face a title, advertising matter, or other indicia as may be desired in accordance with the intended use of the rack.

The lowermost recess 77 may receive indicia, spare tickets, or other miscellaneous items which may be utilized in conjunction with the rack.

A somewhat modified form of the invention may be employed as is disclosed in Figs. 13 to 16 which differ from the disclosure of the preceding figures mainly in that it is substantially rectangular in shape, has marginal portions at the sides as well as at the top and bottom, and has vertical channels for receiving indicia-bearing strips instead of merely the ribs 65.

In Figs. 13 to 16 a panel 78 is provided with upper and lower horizontally disposed members 79 and similar vertically disposed end or side members 80, the panel being preferably provided with an edge molding 81 corresponding to the edge molding 61 of the preceding figures.

Ticket holding strips or slats 63 identical in construction to those utilized in the form of the invention previously described, are mounted in

parallel relation as in the structure of the preceding figures, such strips being secured in position by vertically disposed horizontally spaced ribs 82 corresponding to but wider than the ribs 65 of Fig. 8. The ribs 82 are secured to the panel 78 by screws 83 or other fastening elements.

The vertically disposed ribs 82 in addition to fastening the strips or slats in place divide the rack into a plurality of horizontally spaced areas or sections with ticket receiving pockets 64 in each section, as previously described. There is provided on each rib 82 a channel 84 secured in place by screws 83 or other fastening means, channel 84 serving to removably receive and support an indicia-bearing strip 85 corresponding to strips or slats 63, but being disposed in the channel 84, preferably with the convex surface thereof outermost. The ribs 82 and strips may be disposed at right angles each to the other.

The use of both forms of the invention is best illustrated in Fig. 17 in which a ticket 86 of any desired length is held securely after being inserted in one of the pockets 64. The lower portion of the ticket 86 extends below the bottom edges of one or more of the adjacent strips or slats 63. Tickets of varying lengths may easily be retained in the device, a relatively short ticket extending slightly below the edge of the uppermost strip 63 forming the pocket in which the ticket is inserted with a relatively longer ticket extending below this point, as shown in Fig. 17. Due to the resiliency of the strips or slats 63, the ticket 86 is firmly retained in the pocket 64 since the lower edge of the upper strip 63 resiliently engages the rear surface of the ticket to frictionally hold the same in place, but this frictional engagement is not sufficient to prevent the ready removal of the ticket from the rack. Likewise, the pressure exerted by the lower edge of the uppermost strip or slat 63 upon the rear surface of the next lower strip is not sufficient to preclude the relatively easy insertion of the ticket 86 into the pocket 64 without bending even with tickets of relatively thin material. The pressure is varied in accordance with tension need for thickness of ticket used. If desired the panel 60 or 78 may be omitted and the slats 63 supported by a rectangular framework and the ribs 65 may be duplicated on the rear in order to clamp the slats 63 therebetween.

It will be seen that by the above-described invention there is provided a relatively simple, economical ticket exhibiting and holding rack which may be constructed to accommodate tickets of any desired size and said tickets may be retained firmly in readily available position and in which insertion and removal of the ticket is simple and unimpeded other indicia on the rack also providing means for quickly locating any desired ticket receiving pocket, or a ticket held therein.

The above described invention operates to provide a maximum of service on the part of the dealer or service man and a minimum of time or attention on the part of the car owner. In operation the customer and service man decided on the type of service desired by the customer and the frequency with which such service is to be performed with due regard for the average mileage which the customer may drive during a given period of time and with due regard to the conditions of such driving, i. e. type of roads, speeds, loading of vehicle etc.

The information relative to the service to be performed is entered on a master work sheet 10

there being one of these sheets for each customer, the mileage intervals for service being entered in the basis miles columns and the particular service jobs being indicated by check marks in the appropriate vertical and horizontal columns.

The information provided by the check marks is entered in coded form on the tickets shown in Fig. 2 by crossing out the numbers corresponding to the numbered service operations bearing a check mark on the master sheet. At the same time three numbers are entered on the opposite side of the ticket the upper number designating the customer each of whom is assigned a number when the master sheet is prepared, the second representing the number of days between service visits and the third number representing the number of the ticket which corresponds to the number of the vertical column on the master sheet of Fig. 1 numbered from 1 to 12.

The coded tickets for a given period of maintenance, for instance a year, are placed in a transparent dispenser such as that shown in Fig. 4 and the dispenser installed in the customer's car adjacent the speedometer. It is to be noted that each ticket bears a mileage indication corresponding to the mileage indications in the bases miles columns on the master work sheet. The customer is informed that when the speedometer reading corresponds with the mileage indication on the ticket which is visible he should come in for service.

Upon reaching the service station the visible top ticket is removed from the dispenser and the service foreman prepares a work order in accordance with the maintenance operations indicated by the crossed out numbers on the ticket.

After completion of the work order the foreman turns the ticket over and from the second number appearing thereon ascertains the number of days until the customer's next visit and by adding that number to that day's date ascertains the date on which the customer may be next expected. From this information the ticket with the rear face outermost is placed in the appropriate pocket 64 of the rack shown in Fig. 8.

Filing of the tickets in the rack as designated above provides a means whereby at a glance the shop foreman or service manager may ascertain what customers are due for service and on what days and therefore more efficiently schedule the work. This also provides visible information as to what customers are overdue thus facilitating a reminder or follow-up service.

It will be seen that the above described system operates in a very simple and efficient manner and after the customer has first indicated his service requirements it is only necessary for him to compare the mileage indication on the visible ticket with the mileage reading on the speedometer and take the car to the service station at the appropriate time the correct services operation then being automatically performed. This reduces the serviceman's overhead, contributes to the efficiency of the car and relieves the car owner of the necessity of indicating what operations he desires performed each time he takes the car in for service. The automatic follow-up feature provided by this system also guards against a lapse of memory on the part of the customer and further contributes to good customer relationships.

While the above-described system and use of the rack illustrated in Fig. 8 is the primary purpose therefor, nevertheless, this rack may obviously be utilized for many other purposes and in

fact in any situation where it is desired to visually support a plurality of cards or tickets which may be readily removed at any time and also, as explained above, which may be of varying dimensions.

The rack illustrated in Figs. 13 to 16 may have many uses, but is particularly suitable to facilitate the scheduling of repair or service work in a garage or service station and serves to provide visual indication of the particular job on which a particular mechanic is employed and the probable time when this job will be completed. This is accomplished by providing cards or tickets in duplicate to be inserted in the appropriate pockets 64 provided by the strips 63, these tickets bearing the name or number of the mechanic, the repair order number and the work to be performed by this mechanic. The original of this ticket is placed in the appropriate pocket to indicate the starting time and the duplicate is likewise placed in the appropriate pocket to indicate the estimated time of completion of the job. In the event another customer comes into the service station, the foreman, by a glance at the board, could immediately tell what mechanic would be available for the required work and when. This system would hold true provided that the time estimates were reliable but in the event unforeseen circumstances arose which prolonged the time of any particular job the clock strip 85 is merely moved to properly adjust the time. In the present instance it will align with the appropriate pocket 64 holding the duplicate which would indicate the correct time at which the job was expected to be completed. When the job is actually started the original ticket is removed from the board and when the job is completed the duplicate is also removed. This provides at a glance an indication of the work actually in progress.

It will thus be seen that by this particular modification of the invention the complete working day of a mechanic or any part thereof in one-half hour or other desired intervals may be scheduled and the rack with the job ticket inserted therein provides a quick visual indication of the work being performed in the shop and permits the shop foreman at any time to accurately predict when a job may be finished or when a mechanic may be expected to be available for a subsequent job.

A modified form of the invention is illustrated in Figs. 18 through 25 wherein an illuminated sign is employed on a rack which is somewhat similar to the racks illustrated in Figs. 8 and 13. The sign is of the interchangeable bulletin type upon which is supported letters 87 which the user may selectively employ to change the text of the sign at convenient intervals. As illustrated, the manager's name may occupy an important position thereon but the use and location of the same is optional.

The sign comprises upper and lower plate or shelf members 88 and 99 respectively and may be maintained in spaced relation by upright slat supporting and tensioning members 90 and 91. The upright 90 may have struck out portions 92 from the slots 93 so that such struck out portions or tongues may engage spaced strips or slats 94 which form the face or letter-carrying portion of the sign.

If desired a trim or molding 95 may be employed at the upper and lower portions of the sign to cover the joint between the plate members 88 and 99 and the spaced strips or slats 94.

said molding retaining the uppermost portion of the top slat and the lowermost portion of the lower slat within the limits of the sign. The upright bracing and slat supporting members 90 may be employed to space and support the letter carrying strips or slats 94 in the manner previously described, the slats 94 being provided with spaced openings 96 through which the struck out portions or tongues 92 may extend. The slats 94 may be retained thereon by means of an angularly disposed tip or tongue extremity 97 on the outward extremity of the tongue 92, thereby maintaining the parts in the proper assembled relation. The slats 94 like the slats 63 of Figs. 8 and 13 are preferably of transversely curved strips of sheet metal. Also as in the earlier figures the slats 94 are spaced apart in a horizontal plane and thereby tend to bow outwardly spacing themselves apart between the upright bracing and slat supporting members 90, in which are connected as shown in Figs. 21 and 22. Where the slats 94 are engaged by the brackets 98 no horizontal spacing of the slats will be evident. However, tensioning and horizontal spacing of the slats 94 may be accomplished by the arrangement of the braces or brackets 90. For example, if the brackets 90 are spaced apart as illustrated in the drawings, relative spacing between the slats 94 will be appreciable, but if the brackets 90 are located closer together as by using a greater number of the same, a lesser spacing of the slats will be had providing a more severe tension between the same.

A modified form of upright slat supporting or bracing member is shown at 90' in Fig. 25. This member is provided with a struck out tongue 92' having a downwardly extending lip or extremity 97'. Member 90' is also provided with a flange 100' to facilitate attachment to the frame of the sign or card exhibiting rack. The manner of application of the modified supporting member 90' is shown in Fig. 28 in which the slats 94 are provided with perforations 96 disposed substantially along the longitudinal center line thereof with the struck out portion or tongue 92' extending through the perforation in each slat and with the downwardly depending lip 97' overhanging and engaging the upper edge of the slat 94 disposed immediately below the opening 96. This structure serves to support and retain the slats in proper operative position.

The location of the brackets 90 is preferably proportionate to the lettering to be supported and which forms the message carried by the sign. Each of the letters 87 is provided with one or more rearwardly extending arms 98 having downwardly depending legs 99, these legs to be inserted between the slats 94 for supporting the letters in proper position and allowing light to shine through the opening thus formed to illuminate the letters. The brackets 90 may be of any desired height and likewise may be of any desired width and the number thereof may be supplied in accordance with the customer's particular needs. Also, the brackets 90 and 91 may have angularly disposed upper and lower flange portions 100 for rigid attachment to the upper and lower plate or shelf members 88 and 89 by means of a rivet 101 or other fastening element extending through openings 102 in the flange 100.

The supporting and embracing members 91 are similar to members 90 except that the members 91 are provided with struck out portions 91' which do not engage around the edge of the slat

to clamp the same but merely engage beneath the edge of each slat to prevent sagging of the same or downward movement. Struck out portions or tongues 91' may be seen in Figs. 22, 28 and 30.

Due to the flexibility of the slats 94 and the manner in which they are connected by the brackets 90 there may be provided a sharp curve in the sign as illustrated in Fig. 19 and it is in such curved portion that the uprights 91 are employed which permit the slats 94 to flatten in intimate contact with the same as shown in Figs. 19 and 22.

On the lower plate 89 is a longitudinally arranged neon or other light 104 mounted on brackets 105 and powered by electrical energy from a source of supply by a transformer 106 also mounted on the lower plate 89 and deriving its energy through an electric conduit 107, such conduit having a plug 108 on the end of the same.

Rays of light emanating from the bulb 104 will shine between the spaced slats 94 and cause the letters 87 to be visible in silhouette or to be indirectly lighted. Legs 99 hold the slats 94 apart and permit such illumination giving the completed sign an unusual and artistic appearance as well as providing a distinctly legible and easily readable sign.

A further modified form of sign is illustrated in Figs. 26 and 27, such sign being of the simplest and most inexpensive construction and comprising upper and lower plate or shelf members 110 and 111 with a back 112. The slats 94 have their ends attached to forwardly extending extremities 113 and 114 of the back by suitable fastening means such as rivets or the like, the slats 94 being substantially longer than the back 112 and such slats being bent adjacent their ends to space the intermediate portions of the same from the back and thereby provide a light chamber or housing. The slats are held in such bent relation by means of upright brackets 91 identical with those of Fig. 22, the horizontal extremities 100 of which are fastened by rivets 101 to the upper and lower plate members 110 and 111.

On plate member 111 is preferably longitudinally disposed a light in the form of a tube or bulb 104, mounted on brackets 105, and powered by electrical energy from a source of supply by transformer 106 also mounted on the lower plate 111 and deriving its energy through an electric conduit 107, such conduit having a plug 108 on the end of the same. Rays of light from the tube or bulb 104 will shine between the spaced slats 94 so that the silhouette of any letters 115 will be visible as described above, such indirect lighting giving the sign a very attractive and unusual appearance as well as providing a sign which is distinctly legible and easily readable.

The letters of the sign may be of the character of those disclosed in Fig. 24 or, if preferred, like those of Fig. 29 wherein the letter 115 is provided with a rear bracket 116 of relatively thin strip material welded or otherwise secured on its upper end to the upper portion of the letter 115 and having a reversely bent portion 117 at its lower end for hooking beneath the lower edge of a slat to which the same is applied. In applying the letter rear bracket 116 is inserted between the slats and its lower end is hooked beneath a slat. The letter 115 is swung outwardly by its free lower end until the letter is substantially at right angles to the main portion of the bracket whereupon the bracket is snapped over the upper portion of the slat.

In Fig. 30 is disclosed a modified type of sign which consists substantially of a triangular housing including a top and bottom 118 and 119 with a back, not shown, having forwardly extending flanges 119 and 120 to which slats 94 are attached, the bracket 91 being employed for assisting in holding the slats 94 in bent position. Otherwise, the sign is similar to that previously described.

In Fig. 31 is a very simple modified type of sign consisting of a box or housing comprising upper and lower plate members 121 and 122 and end members 123 and 124, such box being mounted on a frame or supporting structure 125. Slats 94 are secured as described in the preceding figures at the front face of the box by means of brackets 90 having struck-out tongues 42 with up-turned portions 97 or downturned portions 97'. This sign may be illuminated as previously described.

Each of the signs disclosed in Figs. 26, 30 and 31 may have an access opening 126 in its rear with a closure 127 slidably mounted in brackets 128 and with an operating handle 129.

While the above signs have all been described as having a back panel or board if desired it is only necessary to provide the rectangular or skeleton frame work to which the slats are attached since the back panel or board performs no function in supporting the side but merely provides a closure therefor and presents a finished appearance at the rear face.

The invention also contemplates the provision and use of a device to facilitate coding of the tickets 18', etc., this device permitting the simultaneous coding of the tickets and the master work sheet. As shown in Figs. 32 and 33 the coding device comprises a generally rectangular frame work 130 this frame being provided with opposed grooves 131 to slidably receive a modified form of master work sheet 132. One end of the frame 130 is open to permit convenient insertion and removal of the work sheet 132. Sheet 132 is identical with master work sheet 10 with the exception that the vertical columns numbered 1 to 12 of work sheet 10 are replaced by twelve rectangular spaces 133 each of which is identical to one of the tickets 18'.

The frame 130 is provided with apertured ears 134 and pivotally mounted between these ears by a rod 135 extending therethrough is a tubular member 136 having a plurality of arms 137, 138, 139 and 140 extending therefrom at substantially right angles. Arm 137 is provided with a downwardly opening groove 141 and arms 138 and 139 are provided with upwardly extending grooves 142 and downwardly extending grooves 143. Arm 140 is provided with an upwardly opening groove 144. Arms 137, 138, 139 and 140 are provided with abutments 145 adjacent their inner ends the purpose of which will be presently described.

In the operation of the device shown in Figs. 32 and 33 tickets 18', etc. are inserted in the grooves 141 and 142 and likewise in the remaining grooves until the required number of tickets have been received. The arms 137, 138, 139 and 140 together with the tubular member 136 are rotated about the rod 135 to bring the tickets 18' into superimposed registering relation to the spaces 133 on the master sheet 132. At this time it is only necessary to utilize a punch to punch out the required numbered spaces on the tickets and in the spaces 133 of the work sheet 132 thereby simultaneously recording the coding information on both the tickets and the work sheet

132 to indicate the desired service operations for each visit of the customer. This precludes the necessity for manually marking both the master sheet and the tickets which is a time consuming operation and may well result in error. The abutments 145 on the arms 137, 138, 139 and 140 provide a convenient means for accurately locating the tickets 18' when they are inserted in the grooves in the arms, thus insuring registration with the rectangular spaces 133 on the master sheet 132. Obviously a suitable abutment will be supplied on the frame work 130 to insure the proper location or position of the master sheet 131.

The above described system and apparatus provides a convenient and efficient manner of operating a repair or service station in order to maintain overhead costs at a minimum and at the same time provides fast and efficient service for the customer and one in which the customer need only concern himself with providing the service man with information as to his service requirements at the beginning of the servicing period; the system thereafter automatically taking care of all matters, it only being necessary for the customer to compare the mileage reading on the top ticket in his dispenser with the mileage reading on the speedometer and take the car in for service. This system also provides a convenient follow-up feature whereby the service man may ascertain which customers are overdue and contact these customers by mail or phone in order to insure that their cars are properly serviced. The apparatus also provides a convenient means for simultaneously coding the tickets and master work sheet whereby human error is reduced to a minimum and the racks or supporting means for the tickets provide instantly available, visible information, the scheduling rack whereby the mechanics in the shop are assigned their work providing information to the shop superintendent as to when work is completed, actually what work is in progress and enables him to accurately predict when a specified job will be done and to inform a prospective customer when his work will probably be started. The ticket supporting and display rack of this invention may likewise find wide application in other fields of endeavor, their use not being restricted to the particular service operations described in this application.

The system described above together with the apparatus is relatively inexpensive to install and in view of the very material contribution to shop efficiency and to vastly improved customer relationships, the financial standing and sense of well being of both the service man and the customer is greatly improved.

It will be obvious to those skilled in the art that various changes may be made in the invention without departing from the spirit and scope thereof and therefore this invention is not limited by that which is shown in the drawing or described in the specification, but only as indicated in the appended claims.

What is claimed is:

1. Equipment for use in the recording of automobile maintenance services to be rendered and the planning and performance thereof comprising in combination a master work sheet having indicated thereon a numbered list of maintenance services, a plurality of spaces, each space having boxes numbered in accordance with said list, said sheet also indicating the mileage intervals between service calls as well as specific information regarding the customer and the au-

tomobile to be serviced, a series of tickets identical in size and shape to said spaces and having numbered boxes corresponding to the numbered boxes in each of said spaces, each ticket also bearing information indicating the mileage at which the service designated should be performed, the name of the customer, the time interval between service calls and the number of the ticket, means for facilitating the simultaneous recording of coded information indicating the services to be performed on both said tickets and said master sheet comprising a rectangular frame open at one end, grooves in opposed side bars of said frame to slidably receive and support said master sheet, a member pivotally mounted on said frame, bars extending from said member at right angles thereto, said bars having opposed grooves to slidably receive said tickets, abutments on said bars to limit movement of said tickets and accurately position the same with respect to said master sheet supported in said frame, whereby upon pivotal movement of said bars toward said frame the tickets carried thereby will be disposed in superimposed registering relationship with said spaces and coded information may be simultaneously recorded by punching out the appropriate boxes in said tickets and said master sheet, the information on said tickets being de-coded by comparison with said master sheet.

2. Equipment for use in the recording of automobile maintenance services to be rendered and the planning and performance thereof comprising in combination a master work sheet having indicated thereon a numbered list of maintenance services, a plurality of spaces, each space having boxes numbered in accordance with said list, said sheet also indicating mileage intervals between service calls as well as specific information regarding the customer and automobile to be serviced, a series of tickets identical in size and shape to said spaces and having numbered boxes corresponding to the numbered boxes in each of said spaces, each ticket also bearing information indicating the mileage at which the services designated should be performed, the name of the customer, the time interval between service calls, and the number of the ticket, means for facilitating the simultaneous recording of coded information indicating the services to be performed on both said tickets and said master sheet comprising a frame, grooves in said frame to slidably receive and support said master sheet, a member pivotally mounted on said frame, bars extending from said member at right angles thereto, said bars having opposed grooves to slidably receive said tickets, abutments on said bars to limit movement of said tickets and accurately position the same with respect to said master sheet supported in said frame, whereby upon pivotal movement of said bars toward said frame the ticket carried thereby will be disposed in superimposed registering relationship with said spaces and coded information may be simultaneously recorded by punching out the appropriate boxes in said tickets and said master sheet, the information on said tickets being de-coded by comparison with said master sheet.

3. Equipment for use in the recording of automobile maintenance services to be rendered and the planning and performance thereof comprising in combination a master work sheet having indicated thereon a numbered list of maintenance services, a plurality of spaces, each space having boxes numbered in accordance with said

list, said sheet also indicating the mileage intervals between service calls as well as specific information regarding the customer and automobile to be serviced, a series of tickets identical in size and shape to said spaces and having numbered boxes corresponding to the numbered boxes in each of said spaces, each ticket also bearing information indicating the mileage at which the services designated should be performed, the name of the customer, the time interval between service calls, and the number of the ticket, means for facilitating the simultaneous recording of coded information indicating the services to be performed on both said tickets and said master sheet comprising a frame, means on said frame to receive and support said master sheet, a member pivotally mounted on said frame, means extending from said member to receive and accurately position said tickets with respect to said master sheet supported in said frame, whereby upon pivotal movement of said means toward said frame tickets carried thereby will be disposed in superimposed registering relationship with said spaces and coded information may be simultaneously recorded by punching out the appropriate boxes in said tickets and said master sheet, the information on said tickets being decoded by comparison with said master sheet.

4. Equipment for use in the recording of maintenance services to be rendered and the planning and performance thereof comprising in combination a master work sheet having indicated thereon a numbered list of maintenance services, a plurality of spaces, each space having boxes numbered in accordance with said list, said sheet also indicating the intervals between service calls as well as specific information regarding the customer and the device to be serviced, a series of tickets substantially the size and shape of said spaces and having numbered boxes corresponding to the numbered boxes in each of said spaces, each ticket also bearing information indicating the time at which the services designated should be performed, the name of the customer, the time interval between service calls and the number of the ticket, means for facilitating the simultaneous recording of coded information indicating the services to be performed on both said tickets and said master sheet comprising a frame, means on said frame to receive and support said master sheet, a member pivotally mounted on said frame, means extending from said member to receive and accurately position said tickets with respect to said master sheet supported in said frame, whereby upon pivotal movement of said means toward said frame the tickets carried thereby will be disposed in superimposed registering relationship with said spaces and coded information may be simultaneously recorded by punching out the appropriate boxes in said tickets and said master sheet, the information on said tickets being decoded by comparison with said master sheet.
